CLAIM

The ornamental design for a shoe sole, as shown and described.

DESCRIPTION

FIG. 1 is a perspective view of a shoe sole showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is a side perspective view thereof shown in the position of use; the broken line showing of a shoe being for illustrative purposes only and forming no part of the claimed design.

The broken line showing of the shoe in FIG. 8 is for illustrative purposes only and forms no part of the claimed design.
